CLAIM

The ornamental design of a collapsible crab trap, as shown and described.

DESCRIPTION

FIG. 1 is a front perspective view of a collapsible crab trap showing my new design;

FIG. 2 is a front elevational view thereof;

FIG. 3 is a rear elevational view thereof;

FIG. 4 is a side elevational view thereof with the other side elevational view being identical;

FIG. 5 is a top view thereof;

FIG. 6 is a bottom view thereof;

FIG. 7 is a front perspective view thereof showing the doors in an open position; and,

FIG. 8 is a front perspective view thereof showing the design in a collapsed position.
